UNITED STATES PATENT OFFICE.

MORTON H. STARR, OF ST. JOHNSBURY, VERMONT, ASSIGNOR TO E. AND T. FAIRBANKS AND COMPANY, OF ST. JOHNSBURY, VERMONT, A CORPORATION OF VERMONT.

POISE FOR WEIGH BEAMS.

Application filed May 8, 1922. Serial No. 559,176.

To all whom it may concern:

Be it known that I, MORTON H. STARR, a citizen of the United States, residing at St. Johnsbury, in the county of Caledonia and State of Vermont, have invented certain new and useful Improvements in Poise for Weigh Beams, of which the following is a full, clear, and exact description, such as will enable others skilled in the art to which it appertains to make and use the same.

This invention relates to improvements in poise construction for weigh-beams for use with scales, and particularly in some of its details, for use with high capacity scales such as are adapted for installation on railway tracks.

The invention has for its general object improvements in poise construction for weigh-beams or the like, providing a poise which is relatively simple, reliable and exact in function under varying conditions of service, and susceptible of operation with a minimum of effort.

Another object is to provide an improved locking means operating mechanism therefor and for other operative elements of poises of the class mentioned, automatically securing the poise in different operative positions whereby operation is simplified and facilitated.

Still another object is to provide an improved means for locking a poise of the class mentioned to the supporting weigh-beam, so arranged as to remain automatically in unlocked position, simplifying the operation of adjusting the poise along the weigh-beam and balancing the scale.

Other objects will be in part obvious from the following detailed description of an illustrative embodiment, and will be in part pointed out in connection therewith.

The invention accordingly consists in the features of construction, combinations of elements and arrangement of parts which will be exemplified in the construction hereinafter set forth, and the scope of their application will appear in the appended claims.

For a complete understanding of the na-

ture of the invention reference should be had to the accompanying drawings wherein is disclosed the best form at present known, and to the detailed description thereof. In said drawings,

Figure 1 is a fragmentary front elevation of a weigh-beam and poise embodying the invention;

Fig. 2 is a rear elevation, certain parts being broken away more clearly to disclose the structure, the locking mechanism being shown in unlocking position;

Fig. 3 is a sectional view taken on the line 3—3 of Fig. 1; looking in the direction indicated by the arrows;

Fig. 4 is a horizontal section taken approximately on the line 4—4 of Fig. 2 looking in the direction of the arrows, and

Fig. 5 is a detail perspective view showing the operating cam and slide.

Referring to the drawing for a detailed description of the embodiment of the invention as shown, the weigh-beam 1 is mounted in any approved manner for connection with the weighing elements of a scale, and is preferably inverted U-shape in cross-section, as disclosed in co-pending application Serial No. 441,554 filed February 1, 1921.

The poise 2 is mounted on the weigh-beam by means of a carriage having rollers 3 arranged in triangular formation for a three-point suspension, being supported on tracks 4 formed on the inner surfaces of the walls of the downwardly extending legs of the weigh-beam, providing runways so the poise may be rolled along or adjusted longitudinally to obtain an approximate balance. Fine adjustment for balancing this scale beam are made by means of an adjustable auxiliary or fractional poise 5 which may be operated by means of a rack and pinion mechanism through a hand wheel or knob 6, as fully set forth in said prior application.

The weigh-beam may be mounted in any approved manner but is preferably mounted as shown in said co-pending application No. 441,544 and is designed particularly for use in connection with high capacity scales such,

for example, as are employed in railway work and the like, but it is to be understood that the construction is susceptible of other application.

5 It is desirable to lock the poise in adjusted position after a balance has been reached while the process of recording weight by appropriate means is being performed. For this purpose there is a locking mechanism 10 including an elongated locking bar 7 carried by one leg of the weigh-beam and extending along the lower edge thereof, and having a downwardly facing toothed or serrated face 8. This locking bar is co-extensive with the range of travel of the poise.

An elongated pawl 9 having a multiple toothed or serrated face 10 is mounted on the poise with its face lying parallel to and in juxtaposition to the face 8 of the locking bar. This pawl is mounted on a slide 11 confined for vertical sliding movement in guide-ways 12 formed in the poise. Compression springs 13 are confined between opposite extremities of the pawl and opposed abutments 14 on the poise, and are held in position by retaining posts 15 removably seated in the pawl extensions and abutments. The terminal portions of springs 13 surround these retaining posts and the springs are thus held removably in position. These springs are normally stressed to urge the pawl into locking engagement with the locking bar to lock the pawl against longitudinal movement. The multiple toothed 35 pawl construction designed for preventing errors in adjustment of the poise is fully explained in said prior application.

The slide 11 has a rectangular opening 16, at the lower side of which is mounted 40 a roller 17 having its periphery extending slightly beyond the inner face of the lower wall of the opening. An operating cam 18 is disposed within said opening, being rigidly mounted on a shaft 19 rotatable in 45 bearings in the poise and carrying an operating handle 20 at its outer extremity. The operating surface of the cam 18 is approximately heart-shaped, and the base 21 being disposed relatively near to the center of rotation the minor ordinate being disposed at 50 this point and increasing therefrom toward the point 22 where the major ordinate is located. This point forms a lobe or projection on the cam face which is reversely curved at opposite sides of the point or apex. These surfaces lie on opposite sides 55 of the dotted line extending through the center of the operating cam shaft, as shown in Fig. 2. The cam face between the base 21 and the apex 22, and extending also somewhat beyond said apex, is adapted to contact with the roller 17 for operation of the slide 11, and the pawl carried thereby against the force of springs 13. A pointer 60 or index 23 is carried by the handle 20, be-

ing adapted to swing over the dial plate 24 to indicate the different positions of the cam shaft.

A coil spring 25 is supported on a post 26 secured to the poise, being wound around the post and having a fulcrum extension 27 lying in position to engage the vertical face of the side wall of the slide opening 16. The working arm 28 of this spring is connected to a pin 29 secured to the cam, an elongated loop being provided to effect this connection. A pin 30 supported by a wall of the poise forms a lug or stop for engagement with the shoulder 31 of the cam, limiting movement of the latter in one direction, as clearly shown in Figs. 2 and 5.

The recording or printing mechanism is shown particularly in Fig. 3. This comprises a type bar 32 carried by the poise, type 33 being mounted thereon and on the adjacent auxiliary or fractional poise 5. A printing hammer or dog 34 is slidably mounted to co-operate with the type to print weights on a ticket which may be inserted in position through the slot 35. The hammer is carried by a plunger 36 connected to the lower extremity of which is a roller 37 lying in a position to co-operate with an eccentric cam 38 mounted on the cam shaft 19. This cam is mounted on the cam shaft with the major ordinate lying at an angle to that of the heart-shaped cam 18.

The locking pawl operating mechanism of the poise is mounted in a cavity or recess formed therein and is protected by a cover plate 40 secured to the face of the poise and also forming a finishing surface therefor. Pointers 41 and 42 are provided for the poise, the former being adapted to pass over a scale to indicate approximate readings, while the latter is mounted upon the fractional poise to pass over a second graduated scale indicating corrections so the exact weight can be read. These movements also bring appropriate type in registry 110 with the hammer 34.

In operating the poise to secure a balance for the scale, the operating handle 20 is turned into vertical position, as indicated in Fig. 1, the index 23 then indicating "open" position. This moves the operating cam 18 into engagement with the roller 17 to move the slide and locking pawl into unlocking position so the teeth thereof will clear those of the locking bar 7, as clearly shown in Fig. 2. At the time this position of the pawl is reached the nose of the lobe 22 of the cam passes slightly beyond the contact point between the cam and roller, and the lug 31 at this time contacts with the stop pin 30. It will thus be seen that the tension of springs 13 tending to force the pawl toward its locking position acts through the roller 17 and the cam lobe to lock the parts in the 130

position shown in Fig. 2. The poise may then be rolled freely along the weigh-beam to reach a balancing position without the necessity of manually holding the handle in its unlocking position. When the point has been reached for an approximate balance, the handle is operated in the opposite direction to the dot and dash line position shown in Fig. 1. The index 23 then indicates locking position and the pawl is permitted to move to locking position under the influence of compression springs 13.

During the movement of the cam from the unlocking position shown in Fig. 2 to the locking position the working arm of spring 25 is moved in a clockwise direction, as viewed in said figure, placing the spring under tension to oppose movement of the cam shaft beyond the locking position. Further movement to dotted line position of this shaft and handle, in a clockwise direction as viewed in Fig. 2, to the "print" position places the spring 25 under tension, and when pressure on the handle 20 is released the shaft will return automatically under this pressure to the "lock" position. During this movement of the cam shaft from the "lock" position to the "print" position the cam 18 will be inoperative to move the pawl 19, the latter then being in locking engagement with the locking bar 8, while cam 38 will engage the plunger 36 to move the print hammer 34 to make an impression upon the record ticket. It will be noted that the spring 25 begins to be placed under tension about the time the face of cam 18 first contacts with roller 17 in its counter-clockwise movement from locking position toward unlocking position as viewed in Fig. 2. At this time the fulcrum arm 27 contacts with the wall of the opening 16 as described. It is further noted that the springs 25 are relatively weak in comparison with springs 13 so as to exert substantially no influence on the latter in their action tending to move the locking pawl toward locking position.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention, which, as a matter of language, might be said to fall therebetween.

Having described my invention, what I claim as new and desire to secure by Letters Patent, is:

1. In a weighing device, in combination, a weigh-beam, a poise supported by said weigh-beam and movable thereon, means for locking said poise on said weigh-beam, means for operating said locking means, weight printing mechanism, said operating means when operated one way being adapted to automatically hold said locking means, in unlocking position, and when operated another way being adapted to sequentially lock the poise and operate said printing mechanism. 70

2. In a weighing device, in combination, a weigh-beam, a poise supported by said weigh-beam and movable thereon, a locking pawl for said poise, having an elongated locking face and normally biased to locking position, said pawl being mounted so that said locking face moves parallel to itself, means for operating said locking pawl, and automatic means for holding said locking pawl in unlocking position in opposition to said bias. 80

3. In a weighing device, in combination, a weigh-beam, a poise supported by said weigh-beam and movable thereon, a movably mounted pawl for locking said poise against movement, means for holding said pawl in locking position, means for operating said pawl, and automatic means for holding said pawl in unlocking position. 90

4. In a weighing device, in combination, a weigh-beam, a poise supported by said weigh-beam and movable thereon, a slidably mounted pawl for locking said poise against movement, means for normally holding said pawl in locking position, and automatic means for rendering said first mentioned means ineffective to move said pawl into locking position. 100

5. In a weighing device, in combination, a weigh-beam, a poise supported by said weigh-beam and movable thereon, a bodily movable pawl for locking said poise against movement, means for normally holding said pawl in locking position, means for moving said pawl into unlocking position, and means rendered effective by operation of said moving means for holding said pawl in unlocking position. 110

6. In a weighing device, in combination, a weigh-beam, a poise supported by said weigh-beam and movable thereon, a bodily movable pawl for locking said poise against movement, springs normally tensioned for holding said pawl in locking position, a manually operable cam mechanism for moving said pawl to unlocking position, and means rendered effective by operation of said cam mechanism for holding said pawl in unlocking position in opposition to the tension of said springs. 120

7. In a weighing device, in combination, a weigh-beam having a toothed or serrated surface extending therealong, a poise sup- 130

- ported by said weigh-beam and movable thereon, a pawl having an elongated serrated face, means for moving said pawl for engaging said faces to each other to lock 5 said pawl in position, means for releasing said locking engagement, and automatic means depending upon operation of said releasing means for holding said pawl in released position.
- 10 8. In a weighing device, in combination, a weigh-beam having a serrated surface extending therealong, a poise supported by said weigh-beam and movable thereon, a pawl mounted for bodily movement on said 15 poise and having an elongated serrated surface, resilient means mounted on said poise for holding said pawl with said surfaces in engagement with each other to lock said pawl in position, cam mechanism for releasing said locking engagement, and automatic means depending upon operation of said cam mechanism for holding said pawl in released position.
9. In a weighing device, in combination, 25 a weigh-beam, a poise supported by said weigh-beam and movable thereon, means for locking said poise against movement, means for operating said locking means, automatic means for holding said locking means in un- 30 locking position, and printing mechanism operatively connected to said moving means and operable only when said locking means is in said locking position.
10. In a weighing device, in combination, 35 a weigh-beam, a poise movably supported by said weigh-beam, a locking pawl carried by said poise, cam mechanism for operating said pawl, and locking means operatively connected to said cam mechanism for hold- 40 ing said pawl in unlocking position.
11. In a weighing device, in combination, a weigh-beam, a poise movably supported by said weigh-beam, a locking pawl carried by said poise, cam mechanism for supporting 45 said pawl and having a cam face operatively connected to said pawl, said cam face being provided with a lobe for locking said pawl in unlocking position.
12. In a weighing device, in combination, 50 a weigh-beam, a poise movably supported by said weigh-beam, a locking pawl carried by said poise, a cam for operating said pawl having a cam face with a contact connection to said pawl, said cam face being pro- 55 vided with a projecting lobe, and means for stopping said cam when said lobe has passed beyond the line between the center of rotation of said cam and its operating contact point.
- 60 13. In a weighing device, in combination, a weigh-beam, a poise movably supported by said beam, a slide mounted on said poise, a locking pawl carried by said slide and normally biased for co-operation with said 65 weigh-beam for locking the poise in posi- tion, and a cam co-operating with said slide in contacting relationship for moving said pawl to unlocking position in opposition to said bias, said cam being formed to automatically lock said pawl in unlocking 70 position.
14. In a weighing device, in combination, a weigh-beam, a poise movably supported by said weigh-beam, a slide mounted on said poise, a locking pawl carried by said slide, 75 normally biased to co-operate with said weigh-beam for locking the poise in position, a cam co-operating with said slide in contacting relationship for moving said pawl to unlocking position in opposition to 80 said bias, a lobe for said cam positioned so the nose thereof passes beyond the operative contact point of the cam when the pawl is moved to unlocking position, and a stop for holding the pawl in unlocking position and permitting the poise to be freely moved along the weigh-beam to balancing position.
15. In a weighing device, in combination, a weigh-beam, a poise movably supported by said weigh-beam, a locking pawl carried by said poise, spring mechanism for normally holding said pawl in position to lock said poise, cam mechanism for operating said pawl and automatically holding it in one position against the influence of said 90 spring mechanism to hold the pawl in un- 95 locking position, and a second spring mechanism operatively connected to said cam and tensioned to hold the same in another position.
16. In a weighing device, in combination, a poise, a locking pawl for said poise, resilient means for holding said pawl in locking position, cam means for operating said pawl against opposition of said resilient means, a spring operatively connected to said cam means and being stressed to exert pressure on said cam means, and means for relieving the stress on said spring when the cam is moved toward the position corresponding to 105 the locking position of said pawl.
17. In a weighing device, in combination, a poise, a locking pawl mounted on said poise, and a heart-shaped cam for operating said pawl and automatically holding said pawl in a predetermined position.
18. In a weighing device, in combination, a poise, a locking pawl slidably mounted on said poise, resilient means normally urging said pawl to locking position, and a heart-shaped cam co-operating with said pawl for normally holding it in unlocking position.
19. In a weighing device, in combination, a poise, a locking pawl mounted for bodily movement on said poise, a heart-shaped cam co-operating with said pawl for holding it in unlocking position, means for operating said cam, printing mechanism controlled by said operating means, resilient means for urging said pawl toward locking position,

and resilient means connected to said cam for urging said means to normal position following a printing operation.

20. In weighing device, in combination, a poise, a locking pawl for said poise, operating mechanism for said pawl, resilient means normally urging said pawl to locking position, a spring connected to said operating means, and means for placing said

spring under stress when said operating mechanism is moved oppositely to its unlocking movement.

In testimony whereof I affix my signature, in the presence of two witnesses.
